UNITED STATES PATENT OFFICE

2,517,505

FRAMEWORK OF MACHINE TOOLS

Marcel Pégard, Paris, France

Application March 25, 1947, Serial No. 736,905
In France May 23, 1942Section 1, Public Law 690, August 8, 1946
Patent expires May 23, 1962

7 Claims. (Cl. 82—32)

2

1 My invention has for its object a new arrangement for the frames of machine tools and especially of drilling machines and its main aim is the simplification of the removal of filings and liquids used for sprinkling the drilling end of the tool.

In such a frame there is a clear upper surface between the slides and within this area are located inclined surface portions into which the filings and sprinkling liquids drop. At the lowermost point of this inclined surface portion a discharge opening is arranged with an outlet into a passageway within the frame through which the filings are removed. Within the frame there is a sloping channel having a slight slope and designed so as to allow the liquids to run into a tank from which it may be returned. The bottom of this channel is at a lower level than the bottom of the passageway so as to prevent the liquids from flowing out through this passageway.

The accompanying drawings illustrate as an example a method of construction of such a framework. In the drawings:

Fig. 1 is a vertical longitudinal section taken through line I—I of the plan in Fig. 2.

Fig. 2 is a plan corresponding to the above.

Fig. 3 is a cross-section drawn through the line III—III of Fig. 2.

Fig. 4 is a plan view taken from underneath.

As will be seen in Fig. 3 of these drawings the space included between the two longitudinal slides 1 and 2 is clear and two inclined surface portions 3, 4 are provided in this area. In Fig. 1, the slope of these inclined surface portions is clearly visible. At the lowest part of these inclined surface portions there are discharge openings 5, 6 discharging into passageways 7 and 8, that lead to the side face 14 of the framework.

Within the frame there is a slightly sloping channel 9 that leads into a container 10 that acts as a tank for the liquid used for sprinkling the workpiece end the tool. A screen 15 is fitted at the exit end of this channel 9.

It will be observed that the bottom of the channel 9 is on a lower level than the bottom of the passageways 7 and 8.

The container 10 is extended at 16 beyond the side face 14 of the framework. In this extension is placed a motor-pump set 12 that is equipped with an inspection gate 13.

The assembly of the frame is in the shape of a strongly ribbed caisson, as shown in the bottom view of Fig. 4, so as to give the least chance to distortion.

5 When the machine-tool is at work, the filings and sprinkling liquids fall on the inclined surface portions 3 and 4. The liquids flow out through the discharge openings 5, 6, drop into the inclined channel 9 and after being filtered through the screen 15 flow into the container 10. Since the bottom of the channel 9 is on a lower level than the removal openings leading into the passageways 7, 8, the liquids used for sprinkling cannot 10 flow through these removal openings. The liquids are returned from the container 10 by the pump 12 that delivers them into the sprinkling-pot.

15 The filings drop gradually on to the inclined surface portions 3 and 4 and fall through the discharge openings 5 and 6 and are removed through the passageways 7 and 8, e. g. with rakes.

When the channel 9 needs cleaning, the screen 15 is removed and a rake is pushed through a 20 port 11, cut in the side of the framework.

What I claim is:

1. In a boring machine and the like machine tool the combination of a frame, two slideways on said frame, hoppers provided between the 25 slideways at a level underneath same adapted to receive the shavings and the liquid falling off the work, passageways transverse to said slideways into which said hoppers open and directed downwardly towards the outside of the frame, a sloping channel arranged transversely of said passageways, the bottom of the channel lying at a lower level than the corresponding ends of the transversal passageways opening therein, a screen placed at the end of said sloping channel, and a tank to receive the oil which has been 30 filtered by said screen.

2. In a boring machine and the like machine tool the combination of a frame, two slideways on said frame, hoppers provided between the 35 slideways at a level underneath same adapted to receive the shavings and the liquid falling off the work, passageways transverse to said slideways into which said hoppers open and directed downwardly towards the outside of the frame, a sloping channel arranged transversely of said passageways, the bottom of the channel lying at a lower level than the corresponding ends of the transversal passageways, means for returning the 40 liquid collected in the container on to the work, a screen placed at the end of said sloping channel, and a tank to receive the oil which has been filtered by said screen.

45 3. In a boring machine and the like machine tool the combination of a reinforced undeformable ribbed frame, two slideways on said frame,

50 55 means for returning the liquid collected in the container on to the work, a screen placed at the end of said sloping channel, and a tank to receive the oil which has been filtered by said screen.

3. In a boring machine and the like machine tool the combination of a reinforced undeformable ribbed frame, two slideways on said frame,

hoppers provided between the slideways at a level underneath same adapted to receive the shavings and the liquid falling off the work, passageways transverse to said slideways into which said hoppers open and directed downwardly towards the outside of the frame, a sloping channel arranged transversely of said passageways, the bottom of the channel lying at a lower level than the corresponding ends of the transversal passageways, a screen placed at the end of said sloping channel, and a tank to receive the oil which has been filtered by said screen.

4. In a machine tool in combination a longitudinal frame having side faces and an upper surface; an inclined surface portion forming part of said upper surface of said longitudinal frame; a sloping channel arranged within said longitudinal frame under said upper surface thereof; a discharge opening at the lowermost point of said inclined surface portion of said upper surface leading into said sloping channel; and a passageway within said longitudinal frame below said upper surface thereof leading from one side face of said frame into said sloping channel at a point located under said discharge opening and above the bottom of said sloping channel.

5. In a machine tool in combination a longitudinal frame having side faces and an upper surface; an inclined surface portion forming part of said upper surface of said longitudinal frame; a sloping channel arranged within said longitudinal frame under said upper surface thereof; a discharge opening at the lowermost point of said inclined surface portion of said upper surface leading into said sloping channel; a removal opening in the wall of said sloping channel located below said discharge opening and above the bottom of said sloping channel; and a passageway within said longitudinal frame under said upper surface thereof connecting said removal opening with one side face of said frame.

6. In a machine tool in combination a longitudinal frame having side faces and an upper surface; an inclined surface portion forming part of said upper surface of said longitudinal frame; a sloping channel arranged within said longitudinal frame under said upper surface thereof; a discharge opening at the lowermost point of said inclined surface portion of said upper surface leading into said sloping channel; a removal opening in the wall of said sloping channel located below said discharge opening and above the bottom of said sloping channel; and a passageway within said longitudinal frame under said upper surface thereof connecting said removal opening with one side face of said frame.

dinal frame under said upper surface thereof; a container connected to said sloping channel at the lower end thereof; a discharge opening at the lowermost point of said inclined surface portion 45 of said upper surface leading into said sloping channel arranged within said longitudinal frame under said upper surface thereof; a removal opening in the wall of said sloping channel located below said discharge opening and above the bottom of said sloping channel; and a passageway within said longitudinal frame under said upper surface thereof connecting said removal opening with one side face of said frame.

7. In a machine tool in combination a longitudinal frame having side faces and an upper surface; an inclined surface portion forming part of said upper surface of said longitudinal frame; a sloping channel arranged within said longitudinal frame under said upper surface thereof; a discharge opening at the lowermost point of said inclined surface portion of said upper surface leading into said sloping channel arranged within said longitudinal frame below said upper surface thereof; and a passageway within said longitudinal frame under said upper surface thereof leading from one side face of said frame into said sloping channel at a point located under said discharge opening and arranged in such a manner as to prevent unintentional flow of oil from said 70 sloping channel through said passageway.
